By Carl Miller

Edward S. Kadlec Inventor

Attorney

UNITED STATES PATENT OFFICE

EDWARD S. KADLEC, OF NEW YORK, N. Y.

AUTOMATIC ADVERTISING DISPLAY BOOK

Application filed November 26, 1929. Serial No. 409,903.

My invention relates to automatic advertising display books, and the like.

An important object of the invention is to provide a device of this character which will command the instant attention of an observer when the display book is placed into opened position before such an observer, or prospective purchaser.

Other features and advantages of the invention will appear clearly from the detailed description given hereinafter, and the accompanying drawings, in which the same reference numerals indicate like parts throughout the several views, and wherein:

15 Figure 1 is an angular view of the automatic advertising display book, showing the book in open position with the advertising surface in upright position given a full display.

20 Figure 2 is a sectional view of the device taken on the lines 2—2 of Figure 1, looking in the direction of the arrows.

Figure 3 is a diagrammatic plan view showing a modification of the device.

25 Figure 4 is a side view of a fragmentary portion of the book in a nearly closed position.

Referring now more particularly to the drawings, this invention comprises, essentially at least, a pair of pages represented by reference numerals 10 and 11. These pages 10 and 11 may be made out of any suitable or desirable material, such as cardboard, etc., which are hinged together side by side by a binding 12, all of which is of conventional design or construction. Upon each of these pages 10 and 11 there are mounted a series of movable advertising display surfaces 13, likewise of suitable material, which are permanently secured by a portion thereof at its bases 14 to the pages 10 and 11. At the juncture of the base, a lengthwise fold 16 is given to each of the display surfaces 13, as more especially illustrated in Figures 2 and 3. At the upper portion of the pages 10 and 11, strings 17 and 18 of sufficient strength are anchored at points 19 and 20, which are relatively close to the outer border of said pages. Each of these strings 17 and 18 then connect each of the movable advertising display surfaces 13 with each other, such as at fixed

points 15, being approximately midway from the top edge of the display surface and the lengthwise fold 16. Now, these strings 17 and 18 gradually tend to approach each other as they near the lowermost display surfaces, indicated by 13^a, and from each of these lowermost display surfaces 13^a, said strings actually cross each other and are fastened or secured upon the opposite pages at points 21 and 22.

In the modification of the invention shown in Figure 3, an additional column of series of advertising display surfaces 13^b are secured together by strings 17^a and 18^a, which are approximately parallel for a distance to strings 17 and 18 respectively. However, these strings 17 and 18, and 17^a and 18^a are all secured together at points 21^a and 22^a and from these points continue along and cross to the opposite pages where they are affixed thereto at 23 and 24, in the same manner as described in the preferred form.

Mode of operation

The automatic advertising display book is normally carried in closed position, as shown in Figure 4, when not in use. When it is desired to display the advertising matter or educational matter that may be imprinted or attached to the display surfaces, the book is merely opened up, and due to such action, the display surfaces are caused to assume an upright, or nearly upright position, due to the string tightening up between the leaves and the fixed ends 21 and 22 upon the bottom of the opposite pages, inasmuch that the distance therebetween naturally is increased. The exact or desired angle that the display surfaces are to assume with its base, when the book is fully opened, can be satisfactorily adjusted as may be desired, by merely changing the length of string between its secured ends 19 and 20 and the display surfaces.

When the book is closed, the reverse operation takes place, the strings become slack between its fixed points, so that the display surfaces double over at the fold, thereby facilitating the complete closure of the book.

It will be obvious that I have devised a

novel and useful arrangement of an advertising display, which embodies the features of advantages enumerated as desirable, in the statement of the invention and the above description, and while I have, in the present instance, shown and described a preferred embodiment thereof, and one modification of the invention, it is to be understood that the same is susceptible of further modifications, such as, the number of columns of the series of advertising display surfaces, which may be increased to any desired number, likewise the number of rows of the series of advertising display surfaces may vary as may be desired, as well as the number of pairs of pages that form the book, all of which will not depart from the spirit or scope of the invention, or sacrifice any of its advantages.

Having thus described my invention, what I claim as new and desire to secure by Letters Patent is:—

1. An automatic advertising display book, comprising a plurality of pages, movable display surfaces, said display surfaces being hingedly mounted upon said pages, means secured to said display surfaces and to said pages for causing said display surfaces to assume a raised position when the book is placed in open position.

2. An automatic advertising display book, comprising a plurality of pages, movable display surfaces, said display surfaces being hingedly mounted upon said pages, means secured to said display surfaces and to said pages limiting the distance the display surfaces may be raised when the book is opened.

3. An automatic advertising display book, comprising a plurality of pages, movable display surfaces, said display surfaces being hingedly mounted upon said pages, an operating string secured to said display surfaces and to said pages for causing said display surfaces to assume a raised position when the book is placed in open position.

4. An automatic advertising display book, comprising a plurality of pages, movable display surfaces, said display surfaces being hingedly mounted upon said pages, a string secured to said display surfaces and to said pages limiting the distance the display surfaces may be raised when the book is opened.

5. An automatic advertising display book, comprising a plurality of pages, a series of movable display surfaces, said display surfaces being hingedly mounted upon said pages, a plurality of operating strings secured to said display surfaces and to said pages for causing said display surfaces to assume a raised position when the book is placed in open position.

6. An automatic advertising display book, comprising a plurality of pages, a series of movable display surfaces, said display surfaces being hingedly mounted upon said

pages, a plurality of strings secured to said display surfaces and to said pages limiting the distance the display surfaces may be raised when the book is opened.

7. An automatic advertising display book comprising a plurality of pages having a common hinge, a plurality of movable display surfaces hingedly mounted upon each page, an operating string having one end anchored to one page and connected to the plurality of the display surfaces on the opposite page to raise the display surfaces as the book is opened, the other end of said string being anchored to the said opposite page to limit the opening of the book.

8. An automatic advertising display book comprising a plurality of pages having a common hinge, a plurality of movable display surfaces hingedly mounted upon each page, an operating string having one end anchored to one page and connected to the plurality of the display surfaces on the opposite page to raise the display surfaces on that page as the book is opened, the other end of said string being anchored to the said opposite page to limit the raising of the display surfaces, and a second string having one end anchored to the opposite page and connected to a plurality of the display surfaces on said opposite page, said second string having its opposite end crossing said first string, and having its other end anchored on said first page.

9. An automatic advertising display book comprising a plurality of pages having a common hinge, a plurality of movable display surfaces mounted upon each page, the mounting means for this said display surface comprising a plurality of parallel hinges, whereby said display surfaces are movable parallel to each other, an operating string having one end anchored to one page and connected to a plurality of the display surfaces on that page, the other end of said string being anchored to the opposite page.

10. An automatic advertising display book comprising a plurality of pages having a common hinge, a plurality of movable display surfaces mounted upon each page, the mounting means for this said display surface comprising a plurality of parallel hinges, whereby said display surfaces are movable parallel to each other, an operating string having one end anchored to one page and connected to a plurality of the display surfaces on that page, the other end of said string being anchored to the opposite page, and a second string having one end anchored to the opposite page and connected to a plurality of the display surfaces on said opposite page, said second string having its opposite end crossing said first string, and having its other end anchored on said first page.

In testimony whereof I affix my signature.

EDWARD S. KADLEC.
